(57) CLAIM

The ornamental design for a credit card magnifier, as shown and described.

DESCRIPTION

FIG. 1 is a front elevational view of a credit card magnifier showing my new design;

FIG. 2 is an end elevational view from the first end of the design of FIG. 1, both ends of the design being identical;
FIG. 3 is an elevational view of the first side of the design of FIG. 1, both sides of the design being identical;
FIG. 4 is a back elevational view of the design of FIG. 1; and,

FIG. 5 is a perspective view of the second side of the design shown in FIG. 1 from the top, one end, and one side.
